(57) **CLAIM**

The ornamental design for a crutch, as shown and described.

DESCRIPTION

FIG. 1 is a perspective view of a crutch showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged lower portion thereof taken from a lower portion of FIG. 1.

The broken lines are included for the purpose of illustrating portions of the article and form no part of the claimed design.

1 Claim, 8 Drawing Sheets

Related U.S. Application Data

and having an international filing date of Jun. 18, 2018, now abandoned.
